UNITED STATES PATENT OFFICE.

JOHN G. BROTHWELL, OF TORRINGTON, CONNECTICUT, ASSIGNOR TO THE
TURNER & SEYMOUR MANUFACTURING COMPANY, OF SAME PLACE.

DESIGN FOR A WINDOW-SHADE PULL.

SPECIFICATION forming part of Design No. 16,035, dated April 14, 1885.

Application filed March 9, 1885. Term of patent 7 years.

To all whom it may concern:

Be it known that I, JOHN G. BROTHWELL, of Torrington, in the county of Litchfield and State of Connecticut, have invented a new Design for Window-Shade Pulls; and I do hereby declare the following, when taken in connection with accompanying drawings and the letters of reference marked thereon, to be a full, clear, and exact description of the same, and which said drawings constitute part of this specification, and represent, in—

Figure 1, a face view; Fig. 2, a transverse section on line *x x*.

This invention relates to a design for a window-shade pull; and the design consists in a longitudinal rod with the representation of a radially-projecting spiral rib around it, terminating at its two ends in ornamental shape, as shown and hereinafter described.

A central rod, *a*, is represented, around which is the representation of two radially-

projecting spiral ribs, *b b*, forming a double twist around the rod. At the two ends an ornamental termination is made—say as by an arrow-head at one end and tip at the opposite end. The essential feature of the invention is the central longitudinal rod with the radially-projecting spiral rib around it, with an ornamental termination at each end, substantially as shown in the accompanying illustration.

I claim—

The design for a window-shade pull, consisting of the representation of a longitudinal bar having a radially-projecting rib wound spirally around it, terminating at its two ends in ornamental shape, substantially as shown and described.

JOHN G. BROTHWELL.
